UNITED STATES PATENT OFFICE

2,679,219

SEWING MACHINE

Otto Hess, Ludwigsburg, Wurttemberg, Germany

Application June 24, 1952, Serial No. 295,183

Claims priority, application Germany
June 27, 1951

6 Claims. (Cl. 112—162)

1

The invention concerns a sewing machine, particularly the stand of a sewing machine preferably appointed to produce overlock seams, chain stitches and double locked stitches.

It is the object of the invention to avoid—in a high speed sewing machine which must be very intensely lubricated, f. i. by a centralized oil lubricating system—that lubricating oil may be sprayed upon the worked cloth by moving machine parts located in the stand of the sewing machine.

A further object of the invention is to avoid that the downy fiber particles and dust generated during the sewing operation penetrate into the stand, that means to the moving parts located therein, which causes a premature wear of the same.

The sewing machine stands of conventional design are not constructed to avoid in any case the abovenamed disadvantages. The present invention concerns a sewing machine, particularly a stand of such a machine, which is designed in such a way that the abovenamed drawbacks are avoided.

Accordingly, in a sewing machine especially appointed for making overlock seams, chain stitches and double locked stitches the stand comprises a case and an oil pan arranged below said case, a main driving shaft mounted in the case, a pulley fixed on said main driving shaft outside the case for rotating said main driving shaft, a vertical partition wall in the case, arranged substantially parallel to the main driving shaft and partitioning the case into a larger interior compartment and a narrower outer compartment, a second partition wall provided in the interior compartment of the case and arranged rectangular to the main driving shaft and to the first partition wall and subdividing the interior compartment into a larger part and a smaller part, said second partition wall being provided with an opening connecting together the smaller and the larger part of the interior compartment and with a bore in which the main driving shaft rests, an upper looper and a lower looper, both being adapted to take up the thread and to execute oscillating swinging motions around their respective axis, said loopers being disposed in the outer compartment of the case, an upper looper shaft, located in the smaller part of the interior compartment and mounted in the first partition wall and in a block provided in the smaller part of the interior compartment, said upper looper shaft penetrating through the first partition wall into the outer compartment, the upper looper being fixed to the end of the upper looper shaft

projecting out of the said partition wall, a lower looper shaft arranged in the larger part of the interior compartment and mounted in the first partition wall and in a block integral with said partition wall, said lower looper shaft penetrating through said partition wall into the outer compartment, the lower looper being attached on the end of the lower looper shaft projecting out of said partition wall, means operated by the main driving shaft and adapted to impart oscillating swinging movements to the upper looper shaft, means operated by the upper looper shaft and adapted to impart oscillating swinging movements to said lower looper shaft, said last-named means penetrating through said opening, and a cover adapted to seal the smaller part of the interior compartment at the ceiling and at a front side of the interior compartment.

Other and further objects of the invention and details of it will appear from the following description and from the accompanying drawings which show, for purposes of illustrating the present invention, one embodiment in which the invention may take form, it being understood that the drawings are only illustrative of the invention and not limiting the same.

In these drawings:

Fig. 1 is a side view of the stand case of the sewing machine, the outer compartment of which has been made visible by taking away a cover and a part of one outer wall,

Fig. 2 is a top view of the stand case of the sewing machine, all parts situated above the case being omitted,

Fig. 3 is a side view of the stand case, the cover being omitted,

Fig. 4 is a side view, partly in section, of the stand case,

Fig. 5 is an enlarged vertical section of a partition wall of the case, in which partition wall the upper and the lower looper shafts are mounted,

Fig. 6 is a perspective view of the smaller part of the interior compartment of the stand case, the moving parts being taken off,

Fig. 7 is a perspective view of the cover for the interior compartment shown in Fig. 6.

Figs. 1 and 2 show the stand of a sewing machine being composed of a case 23 and an oil pan 24 arranged therebelow. In said case 23 the main driving shaft 3 of the sewing machine is mounted, to which driving shaft a driving pulley 32" is attached outside the case. According to the present invention a vertical partition wall 5 is located substantially parallel to said main driving shaft 3, which partition wall subdivides the

case 23 into a broader interior compartment 1 and a narrower outer compartment 2. A second partition wall 7 is arranged in the interior compartment 1 of the case 23, rectangular to the main driving shaft 3 and to the first partition wall 5, said second partition wall 7 subdividing the interior compartment 1 into a larger portion 1a and a smaller portion 1b.

The partition wall 7 is supplied with a bore 25 in which the main driving shaft 3 is supported, whereas the opposite end of the main driving shaft 3 is mounted in the wall 6 of the case 23.

Furthermore, the partition wall 7 is supplied with an opening 28, connecting together the smaller part 1b and the larger part 1a of the interior compartment.

Moreover, an upper looper 8 and a lower looper 9 are provided, both being adapted to take up a thread and to execute oscillating swinging movements around their respective axes. The loopers 8 and 9, cooperating with the needle 40, are disposed in the outer compartment 2 of the case 23.

An upper looper shaft 12 is provided in the smaller part 1b of the interior compartment and mounted in a bore 29 of the partition wall 5 and in a bore 30 of a block 31, provided in the part 1b of the interior compartment. The upper looper shaft 12 penetrates through the partition wall 5 into the outer compartment 2. There the upper looper 8 is attached to a clip 27 by means of a screw 32, the clip in turn being clamped, by means of a screw 26, to the end 10 of the upper looper shaft 12 projecting out of the partition wall 5.

A lower looper shaft 13 is arranged in the larger portion 1a of the interior compartment 1 and mounted in a bore 34 of the partition wall 5 and of a block 33 conveniently integral with the partition wall 5. The end 11 of the lower looper wall 13 projects into the outer compartment 2, thereby penetrating through the partition wall 5. The lower looper 9 is fixed, by means of a screw 32', to a clip 27' which, by means of a screw 26', is clamped to the shaft end 11.

A crank web 15, carrying a crank pin 16, is secured to the end 14 of the main driving shaft 3 projecting into the smaller part 1b of the interior compartment. A guide rod 17 is articulated to said crank pin 16. The guide rod 17 is supplied with an eye 17a respectively 17b at both ends. Each of the eyes is composed of two halves 17a' and 17a'' respectively 17b' and 17b'', being connected in pairs by screws 34'. The inner bore of the eyes 17a respectively 17b are machined out spherical. The crank pin 16, on its part, has a spherical surface which is articulated in the spherical bore of the eye 17a.

A lever 35 is fixed against rotation upon the upper looper shaft 12. The free end of said lever 35 is supplied with a spherical surface, with which the lever 35 is articulated in the spherical inner surface of the eye 17b.

A forked lever 36 is attached to the guide rod 17 by means of a screw 37, the forked lever extending parallel to and at a distance from the eye 17b. The lever 35 has a pin-shaped end 35' projecting beyond the spherical shaped part of the lever 35. The pin-shaped end 35' engages the forked lever 36.

A further lever 18 is fixed against rotation on the upper looper shaft 12, and, furthermore, a third lever 20 is secured radially upon the lower looper shaft 13. A guide rod 19 is articulated to the free ends of the levers 20 and 18, the guide rod 19 penetrating the opening 28 supplied in the partition wall 7 which connects together the two

parts 1a and 1b of the interior compartment 1. The ends of the levers 18 and 20 also project into the opening 28 during their motion.

The operation of the parts mounted in the case 23 is as follows:

When the main driving shaft 3 rotates, the crank pin 16 operates the guide rod 17 which, through the intermediary of the lever 35 imparts an oscillating swinging movement to the upper looper shaft 12 and accordingly also to the upper looper 8. This oscillating movement, proceeding from the upper looper shaft 12, is transmitted to the lower looper shaft 13 through the lever 18, the guide rod 19 and the lever 20, whereby the lower looper 9, on its part, executes an oscillating swinging motion.

It is obvious from the foregoing description that, outside the interior compartment 1a, 1b, only the upper looper 8, the lower looper 9 and the shaft ends 10 and 11 are located. No moving parts are located in said outer compartment 2, which have to be lubricated. As a result, it is impossible that lubricating oil may penetrate from the outer compartment 2 to the cloth to be sewed, which, according to conventional practice, is separated from the outer compartment 2 by the stitching plate, having gaps for one or two feed dogs.

On the other hand, it is also impossible that downy fiber particles, resulting from the sewing operation, and dust may penetrate through the outer compartment 2 into the interior compartment 1a, 1b, because said two compartments are connected together only by bores 29 and 34, which are filled up by the ends 10 and 11 of the two looper shafts 12 and 13 and the bushings 38 surrounding said shafts. The part 1a of the interior compartment 1, containing the major portion of the moving and therefore lubricated parts, communicates with the adjacent part 1b only by a relatively small opening 28 of the partition wall 7, so that it is avoided also that more lubricating oil than necessary sprays from the room 1a into the room 1b.

In order to place the major portion of the moving parts in the compartment 1a, also the lower looper shaft 13 and the greatest portion of the parts operating said shaft 13 are located in the compartment 1a, unlike the sewing machines of conventional type, with which the lower looper shaft and the parts operating the same are located at a place which, in the case of a case 23 according to the invention, is situated in the part 1b of the interior compartment 1. Furthermore, a simplified drive of the lower looper shaft 13 is accomplished by the arrangement according to the invention. The compartment 1b, at the top and at a front side of the case, is closed by a removable cover 39, which seals completely the interior compartment 1b. As a result, neither lubricating oil may be sprayed to the cloth out of the beforenamed compartment, which is most adjacent to the cloth to be worked, nor downy particles or dust penetrate into said compartment.

What I claim is:

1. In a sewing machine, especially for making overlock seams, chain stitches and double locked stitches, a stand comprising a case and an oil pan mounted below said case, a main driving shaft mounted in the case, a pulley fixed on said main driving shaft outside the case and adapted to drive said main driving shaft, a vertical partition wall in the case, arranged substantially parallel to the main driving shaft and subdividing the case into a larger interior compartment

and a narrower outer compartment, a second partition wall provided in the interior compartment of the case and arranged perpendicular to the main driving shaft and to the first mentioned partition wall and subdividing the interior compartment into a larger portion and a smaller portion, said second mentioned partition wall being provided with an opening interconnecting the smaller and the larger portion of the interior compartment, and with a bore in which the main driving shaft is supported, an upper looper and a lower looper both adapted to take up the thread and to execute oscillating swinging motions around their respective axes, said loopers being disposed in the outer compartment of the case, an upper looper shaft located in the smaller part of the interior compartment and mounted in the first mentioned partition wall and in a block, provided in the smaller part of the interior compartment, said upper looper shaft penetrating through the first mentioned partition wall into the outer compartment, the upper looper being attached to the end of the upper looper shaft projecting out of the partition wall, a lower looper shaft disposed in the larger part of the interior compartment and mounted in the first mentioned partition wall and in a block integral with said partition wall, said lower looper shaft penetrating through the first mentioned partition wall into the outer compartment, the lower looper being secured to the end of the lower looper shaft projecting out of the first mentioned partition wall, means operated by the main driving shaft and adapted to impart an oscillating swinging motion to the upper looper shaft, second means operated by the upper looper shaft and adapted to impart an oscillating swinging movement to the lower looper shaft, said last-named means penetrating through said opening, and a cover provided to close up tightly the smaller part of the interior compartment and at a front side of the interior compartment.

2. In a sewing machine according to claim 1, in which there are provided a crank web arranged on the end of the main driving shaft projecting into the smaller part of the interior compartment of the case, a crank pin secured to the crank web, a guide rod provided with an eye at both ends, each eye consisting of two halves connected together by screws and being supplied with an inner spherical surface, a lever radially fixed to the upper looper shaft, said lever at its free end and the crank pin both provided with a spherical surface, said spherical surfaces being supported in said spherical inner surfaces, a forked lever being secured to the guide rod, parallel and at a distance from the eye surrounding the spherical shaped end of said lever, and a pin-shaped extremity of the lever projecting beyond its spherical shaped end, said pin-shaped extremity engaging said forked lever.

3. In a sewing machine according to claim 1, in which there are provided a lever secured radially upon the upper looper shaft, a further lever secured radially against rotation upon the lower looper shaft, and a guide rod pivotally connected to the free ends of both aforementioned levers and penetrating through the opening which interconnects the smaller and the larger part of the interior compartment.

4. In a sewing machine, especially for making overlock seams, chain stitches and double locked stitches, a stand comprising a case and an oil pan mounted below said case, a main driving

shaft mounted in the case, a vertical partition wall in the case, arranged substantially parallel to the main driving shaft and subdividing the case into a larger interior compartment and a narrower outer compartment, a second partition wall provided in the interior compartment of the case and arranged perpendicular to the main driving shaft and to the first-mentioned partition wall and subdividing the interior compartment into a larger portion and a smaller portion, said second-mentioned partition wall being provided with an opening interconnecting the smaller and the larger portion of the interior compartment, and with a bore in which the main driving shaft is supported, an upper looper and a lower looper both adapted to take up the thread and to execute oscillating swinging motions around their respective axes, said loopers being disposed in the outer compartment of the case, an upper looper shaft located in the smaller part of the interior compartment and mounted in the first-mentioned partition wall and in a block, provided in the smaller part of the interior compartment, said upper looper shaft penetrating through the first-mentioned partition wall into the outer compartment, the upper looper being attached to the end of the upper looper shaft projecting out of the partition wall, a lower looper shaft disposed in the larger part of the interior compartment and mounted in the first-mentioned partition wall and in a block integral with said partition wall, said lower looper shaft penetrating through the first-mentioned partition wall into the outer compartment, the lower looper being secured to the end of the lower looper shaft projecting out of the first-mentioned partition wall, means operated by the main driving shaft and adapted to impart an oscillating swinging motion to the upper looper shaft, and second means operated by the upper looper shaft and adapted to impart an oscillating swinging movement to the lower looper shaft, said last-named means penetrating through said opening.

5. In a sewing machine, especially for making overlock seams, chain stitches and double locked stitches, a stand comprising a case and an oil pan mounted below said case, a main driving shaft mounted in the case, a vertical partition wall in the case, arranged substantially parallel to the main driving shaft and subdividing the case into a larger interior compartment and a narrower outer compartment, a second partition wall provided in the interior compartment of the case and arranged perpendicular to the main driving shaft and to the first-mentioned partition wall and subdividing the interior compartment into a larger portion and a smaller portion, said second-mentioned partition wall being provided with an opening interconnecting the smaller and the larger portion of the interior compartment, and with a bore in which the main driving shaft is supported, an upper looper and a lower looper both adapted to take up the thread and to execute oscillating swinging motions around their respective axes, said loopers being disposed in the outer compartment of the case, an upper looper shaft located in the smaller part of the interior compartment and mounted in the first-mentioned partition wall and in a block, provided in the smaller part of the interior compartment, said upper looper shaft penetrating through the first-mentioned partition wall into the outer compartment, the upper looper being attached to the end of the upper looper shaft projecting out of the partition wall, and a lower looper shaft dis-

posed in the larger part of the interior compartment and mounted in the first-mentioned partition wall and in a block integral with said partition wall, said lower looper shaft penetrating through the first-mentioned partition wall into the outer compartment, the lower looper being secured to the end of the lower looper shaft projecting out of the first-mentioned partition wall.

6. In a sewing machine, especially for making overlock seams, chain stitches and double locked stitches, a case, a main driving shaft mounted in the case, a vertical partition wall in the case, arranged substantially parallel to the main driving shaft and subdividing the case into a larger interior compartment and a narrower outer compartment, a second partition wall provided in the interior compartment of the case and arranged perpendicular to the main driving shaft and to the first-mentioned partition wall and subdividing the interior compartment into a larger portion and a smaller portion, said second-mentioned partition wall being provided with an opening interconnecting the smaller and the larger portion of the interior compartment, and with a bore in which the main driving shaft is supported, an upper looper and a lower looper both adapted to take up the thread and to exe-

cute oscillating, swinging motions around their respective axes, said loopers being disposed in the outer compartment of the case, an upper looper shaft located in the smaller part of the interior compartment and mounted in the first-mentioned partition wall and in a block, provided in the smaller part of the interior compartment, said upper looper shaft penetrating through the first-mentioned partition wall into the outer compartment, the upper looper being attached to the end of the upper looper shaft projecting out of the partition wall and a lower looper shaft disposed in the larger part of the interior compartment and mounted in the first-mentioned partition wall and in a block integral with said partition wall, said lower looper shaft penetrating through the first-mentioned partition wall into the outer compartment, the lower looper being secured to the end of the lower looper shaft projecting out of the first-mentioned partition wall.
